TRAY SUPPORT FOR A HOT FOOD PLATTER

Richard N. Brandon, Dayton, Ohio, assignor to
Ponderosa Systems, Inc., Dayton, Ohio

Filed Aug. 20, 1973, Ser. No. 389,949

Term of patent 14 years

Int. Cl. D7—01

U.S. Cl. D7—21

FIG-1

FIG-4

FIG. 1 is a top perspective view of a tray support for a hot food platter showing my new design;

FIG. 2 is a bottom perspective view thereof;

FIG. 3 is a side elevation thereof; and

FIG. 4 is an end elevational view thereof.

I claim:

The ornamental design for a tray support for a hot food platter, substantially as shown.
